55. Now, according to the method of this invention, the hollow tube is inserted within the tube to be formed so as to overlap the upper end of the tube to be formed and to extend beyond the upper end of the tube to be formed.

UNITED STATES PATENT OFFICE

2,635,291

METHOD OF FINISHING TOPS OF HOSIERY FORMS

Basil Pomeroy Cooper and James Norman Henshaw, Leicester, England, assignors to United Shoe Machinery Corporation, Flemington, N.J., a corporation of New Jersey

Application March 14, 1950, Serial No. 149,488
In Great Britain April 8, 1949

2 Claims. (Cl. 18—47.5)

1

This invention relates to methods of finishing the tops of hollow hosiery forms, commonly made of a plastic material, to avoid damage to hosiery displayed thereon.

For some years hollow hosiery forms molded from plastic material have been used for the display of hosiery in stores and the finishing of the upper end of such forms so that there may be no danger of injuring the hosiery has been costly and has required substantial skill.

One well-known manner of making the forms is described in Letters Patent of the United States 2,222,461, granted November 19, 1940, upon the application of W. J. De Witt et al. There the hollow form is shaped in a suitable die and when withdrawn from the die has a partially closed top comprising an inturned flat top flange integral with the leg of the form. Centrally disposed on this flange and forming an extension thereof is a conical projection which results from the manner of clamping the material in the die and which is usually removed in completing the form, leaving the inturned marginal flange. After this projection or neck has been removed it is necessary to finish the sharp inner edge of the flange by careful work with an abrasive tool together with the application of a solvent to the smoothed edge.

In one aspect the invention resides in an improved method of finishing the tops of such forms which may be carried out cheaply and expeditiously even by unskilled workers.

In utilizing this method the conical neck which is to be discarded is removed by a rotary trimming tool herein illustrated as a trepanning saw and this is followed by the curling of the remaining inturned flange as by presenting the top end of a form to a heated shaping tool which, in the preferred embodiment, has a conical projection which terminates at its inner end in an annular curved recess. The form is pressed against this tool until the heat causes the upper end to curl inwardly and assume the shape of the recess thus leaving a smooth nicely finished end portion which requires very little hand work. The preferred way of carrying out this method is described in the following specification taken in connection with the accompanying drawings in which

Fig. 1 is an axial cross-section through the upper end of a suitable die used for initially molding the form;

Fig. 2 illustrates the presentation of the molded form to the trepanning tool to trim it and cut away the neck thereon;

2

Fig. 3 shows the manner of presenting the resulting trimmed form to a heated shaping tool which causes the marginal flange of the form to curl inwardly; and

Fig. 4 shows the finished condition of one such hosiery form after it has been treated in accordance with our method.

Hosiery forms 10 of the same general character as that shown in Fig. 4 of the drawings have been made from hollow tubes of plastic material substantially in the manner illustrated in the De Witt patent mentioned above by inserting a tube within a two-part mold 12, and closing the mold to pinch the tube at the foot portion thereof so as to close it, and to grip the upper end of the tube within the conical portion 14 of the mold against a plug 16. This plug may be provided with a pipe 18 for the introduction of steam to be used in heating the material of the form 10 to expand it and cause it to fit the inside of the mold and a pipe 20 by means of which the steam may be exhausted from the mold at a later time when a valve, not shown, therein is opened.

The shape of the mold 12, 14 is such that the upper end of the form is partially closed as by an inturned flange 22 which is integral with and merges with the leg portion of the form in a smooth curve. The flange terminates at its inner edge in an upstanding neck 24 which is incidental to the molding operation.

After the molded form has been cooled, to set the plastic in its molded shape, it is removed from the mold and the plug 16 broken out of the neck 24. Thereupon the pinched together portion at 35 the foot is trimmed away and the closed upper portion of the form is subjected to a finishing operation providing a smooth edge so that the form may be introduced in a stocking with the latter overlapping the top portion thereof without danger of injuring the stocking.

In accordance with our improved method of finishing the top of the form, the neck portion 24 thereof is removed by making a cut around the base of the neck where it joins the inturned flange 22. This can be done simply and with considerable precision by introducing the neck portion into a circular cutter 30 which is here shown as a trepanning saw supported in a carrier 32 by means of which it is adapted to be rotated upon a fixed axis. It will be noted that the tapered formation 34 of the lower end of the inner surface of the carrier is substantially the same size as the outer surface of the neck where it joins the flange 22. This will help to center the form in the saw 30 and make it un-

necessary for the operator to use any particular skill in presenting the form to the saw. Obviously it is immaterial whether the form is presented to the saw by movement of it in the direction of the arrow 36 or whether the saw is movably mounted to carry it into contact with the form.

At this point in the finishing operation the form 10 will be left with an inturned flange 22 as shown in Fig. 3 of the drawings. In continuing the finishing process, the upper end of the form 10 is presented to a shaping tool 40 electrically heated by current introduced through wires 42 to a heating element 43. This shaping tool has a frusto conical projection 44 shaped to coact with and contact the inner periphery of the flange 22 as the two are brought together. During this relative movement the position of the form is centralized with respect to the projection 44 by means of a cylindrical guide 46 attached to the tool but prevented from becoming hot by means of an interposed ring 48 of heat insulating material such as asbestos. The inner end of the conical projection 44 converges with the body of the tool 40 in an annular, hemi-toroidal recess 50 which, in radial cross section, is a smooth curve extending out to the maximum diametrical dimension of the top of the form.

Accordingly, when a form the neck portion of which has been removed by means of the trepanning saw shown in Fig. 2 is caused to engage the forming tool 40 shown in Fig. 3 the flange 22 will be softened and caused to curl inwardly at 52 in Fig. 4 thus providing a convenient hand hold for manipulating the form and for carrying it from place to place. Substantially at the end of the upward movement of the form, the flange will be rounded to fit the recess 50, thus imparting the final shape shown in Fig. 4. The guide has slits (not shown) to permit the operator to watch the progress of this shaping step. A minimum of 40 smoothing of the inner edge 54 of this curled-in flange is all that is needed to protect from injury a stocking drawn over the form with the surplus material at the top of the stocking pushed into the the inside through the aperture formed by 45 the incurled flange 52.

Having thus described our invention, what we claim as new and desire to secure by Letters Patent of the United States is:

1. The method of finishing the top end of a hollow plastic hosiery form having the shape of a portion of a human leg, an integral in-turned marginal flange and upstanding tapered neck joined to the inner periphery of said flange, which consists in utilizing the neck to guide the form into cutting engagement with a driven annular trimming tool to cut away the neck, leaving the in-turned flange integral with the form, guiding the cut inner edge of the in-turned flange into engagement with a tapered projection upon 15 a heated forming tool having an annular, hemi-toroidal recess at the inner end of the projection and continuing the relative movement between the form and the tapered projection of the tool to curl the inner edge portion of the flange downwardly directly into the leg portion of the form and to force the exposed top surface of the flange into the hemi-toroidal recess of the tool forming the flange into a hemi-toroidal shape extending from the curled inner edge thereof to the outer 20 surface of the leg portion of the form.

2. The method of finishing the top end of a hollow plastic hosiery form as defined in claim 1 wherein the neck of the form is moved into engagement with a tapered surface within the annular trimming tool to guide the form into cutting engagement therewith.

BASIL POMEROY COOPER.
JAMES NORMAN HENSHAW.
